CLOTHESPIN

Eucliede Lognion, Lake Charles, La.

Application May 19, 1937, Serial No. 143,581

2 Claims. (Cl. 24—261)

This invention relates to a clothes pin, and has for its object to provide, in a manner as herein-after set forth, an article of such class formed of a skeleton-like body consisting of a pair of spring controlled oppositely shiftable clothes grippers normally abutting intermediate their ends and having their outer terminal portions extended in opposite directions and a handle coacting with said terminal portions for facilitating the positioning of the grippers in clothes suspending relation.

A further object of the invention is to provide, in a manner as herein-after set forth, a clothes pin of the spring controlled gripping type in the form of a skeleton body constructed from an endless length of spring wire of the desired gauge and possessing a non-rusting characteristic.

A further object of the invention is to provide, in a manner as herein-after set forth, a clothes pin of the spring controlled gripping type in the form of a skeleton body constructed from an endless length of wire of the desired length and including a pair of coacting clothes grippers, one being provided with a series of spaced offset gripping points for clamping the clothes against the other.

Further objects of the invention are to provide, in a manner as herein-after set forth, a skeleton clothes pin which is simple in its construction, strong, durable, compact, thoroughly efficient in its use, possessing an inherent clothes gripping function, conveniently positioned in clothes suspending relation with respect to a hanger, such as a clothes line, possessing a non-rusting characteristic, and inexpensive to manufacture.

To the above ends essentially and to others which may herein-after appear, the invention consists of the novel construction, combination and arrangement of parts as will be more specifically referred to and as illustrated in the accompanying drawing wherein is shown an embodiment of the invention, but it is to be understood that changes, variations and modifications may be resorted to which fall within the scope of the invention as claimed.

In the drawing:

Figure 1 is a side elevation of the clothes pin, Figure 2 is a top plan view thereof.

Figure 3 is a section on line 3—3, Figure 1.

Figure 4 is a section on line 4—4, Figure 1, and

Figure 5 is a section on line 5—5, Figure 1.

The clothes pin is constructed from an endless length of spring wire of the desired gauge and which possesses a non-rusting characteristic.

The wire is bent in a manner to form a skeleton body 6 formed of a pair of oppositely disposed grippers 7, 8, a pair of parallel controlling springs 9, 10 disposed at right angles to the grippers 7, 8 and a handle formed of a pair of spaced parallel like hand gripping portions 11, 12 extended forwardly and rearwardly with respect to the springs 9, 10. The gripper 7 extends forwardly with respect to the handle portions 11, 12. The gripper 8 extends forwardly with respect to the 10 springs 9, 10. Each of the handle portions is in the form of a resilient loop open at its inner end. The handle portions act to normally maintain the gripper 7 in abutting relation with respect to the gripper 8. The springs 9, 10 act to normally 15 maintain the gripper 8 in abutting relation with respect to the gripper 7.

The gripper 7 is formed of a horizontally disposed curved front part 13 and a pair of spaced parallel side parts 14, 15 of like form. The ends of the part 13 merge into the forward ends of the side parts 14, 15. Each side part includes an upwardly inclined leading stretch 16, an upwardly extending rearwardly inclined outer intermediate stretch 17, a central rearwardly extending 25 downwardly inclined intermediate stretch 18, an upwardly extending rearwardly inclined rear intermediate stretch 19 and a rearwardly extending downwardly inclined rear or follower stretch 20. The lower end of stretch 17 merges into the 30 rear end of stretch 16. The forward end of stretch 18 merges into the upper end of stretch 17. The lower end of stretch 19 merges into the rear end of stretch 18. The forward end of stretch 20 merges into the upper end of stretch 35 19. The stretch 16 is of greater length than stretches 16, 17, 19. The stretch 18 is of greater length than the other stretches. The points of joinder of stretches 16, 17 form gripping points 22. The points of joinder of the stretches 18, 40 19 form gripper points 21. The portions 21 of stretches 18 provide gripper points. The points 21 are normally in abutting engagement with the gripper 8. The stretches 16 in connection with the curved front part 13 provide for the forward 45 end terminal portion of the gripper 7 to extend outwardly at an upward inclination with respect to the gripping points 22. The construction of the gripper 7 forms its inner face with a series of spaced gripping points for the clothes.

The gripper 8 extends forwardly with relation to the front part 13 of gripper 7 and is formed of a horizontally disposed front part 23 and a pair of spaced parallel side parts 24, 25 of like form. The ends of the part 23 merge into the forward 55

ends of the parts 24, 25. The side part 24, as well as the side part 25 consists of a down curved leading stretch 26, a rearwardly extending intermediate stretch 27 which inclines slightly upwardly from front to rear and a rearwardly extending upwardly inclined rear or follower stretch 28. The upper end of stretch 26 merges into the forward end of stretch 27. The lower end of stretch 28 merges into the rear end of stretch 27. The stretch 26 is of less length than the stretches 27, 28. The stretch 27 is of greater length than the stretch 28. The gripping points 22 normally abut the upper terminal portions of the stretches 26. The portions 21 of the stretches 18 align in spaced relation with the stretches 27. The part 23 in connection with the stretches 26 provide for the forward end terminal portion of the gripper 8 extending outwardly with respect to the forward ends of the stretches 27. The forward end terminal portion of the gripper 8 extends in an opposite direction with respect to the forward end terminal portion of the gripper 7. The said forward end terminal portions facilitate the positioning of the pin for the purpose of gripping the clothes to or clamping them on the line.

The controlling springs 9, 10 are formed by a pair of coils. Each stretch 28 of the gripper 8 merges at its rear end into one end of a coil. The coils have their ends positioned at the tops thereof.

Each handle section consists of an upstanding curved rear stretch 29, a forwardly extending downwardly inclined horizontal top stretch 30 and a forwardly extending upwardly inclined bottom stretch 31. The end of the stretch 29 merges into the rear ends of the stretches 30, 31. The forward end of each top stretch 30 merges into the other end of a coil rearwardly of and inwardly with respect to the point of mergence of a stretch 28 with a coil. The bottom stretches 31 have oppositely disposed outcurved forward end terminal portions 32 which merge into the rear

ends of the stretches 20 of the gripper 8. The length of the stretches 29 is greater than that of the part 13 of gripper 7 or the part 23 of gripper 8. The stretches 29 are disposed at right angles to the parts 13, 23 of the grippers. The longitudinal medians of the grippers are disposed at right angles to the axes of the springs. When hand pressure is applied to the stretches 30, 31 of the handle and in a direction to narrow the openings at the inner end of the portions 11, 12 it facilitates, in connection with the forward end terminal portions of the grippers to open these latter to overlap the garment for the purpose of gripping or clamping the latter to the line. The said forward end terminal portions provide what may be termed an entrance passage for the clothes when the pin is moved to active position.

What I claim is:

1. In a clothes pin, a pair of oppositely disposed U-shaped grippers, one having means for normally abutting the other intermediate the ends of the latter, said grippers having their forward end terminal portions extending away from each other to provide an entrance passage for a garment to be gripped to a clothes line, a pair of controlling springs, the sides of one of said grippers merging at their rear ends into the said springs, and a looped handle merging into said springs and in the rear ends of the sides of the other of said grippers.

2. In a clothes pin, a pair of oppositely disposed normally superimposed oppositely shiftable U-shaped grippers, a pair of coiled controlling springs, the sides of the lower one of said grippers merging at their rear ends into said springs, and a looped handle having parts merging into the rear ends of the sides of the upper gripper forwardly of the springs and parts merging into said springs rearwardly of said grippers.

EUCLIEDE LOGNION.
